A. J. LEWIS

SPRING ROLLER FOR SUN VISORS

Filed June 19, 1922

Fig. 1.

Fig. 2.

The diagram shows a cross-section of a cylindrical device. It features a central circular cavity with a ribbed inner wall. A rectangular frame, labeled 10, 11, 12, 13, 14, 15, 16, 17, 18, 19, 20, 21, 22, 23, 24, 25, 26, 27, 28, 29, and 30, is positioned around the cavity. A vertical rod, labeled 31, extends from the bottom through the center of the device. The label 'Fig. 5.' is written in a cursive script across the top right of the diagram.

UNITED STATES PATENT OFFICE.

ATLEE J. LEWIS, OF MANSFIELD, OHIO.

SPRING ROLLER FOR SUN VISORS.

Application filed June 19, 1922. Serial No. 569,227.

To all whom it may concern:

Be it known that I, ATLEE J. LEWIS, a citizen of the United States, residing at Mansfield, in the county of Richland and 5 State of Ohio, have invented a new and useful Spring Roller for Sun Visors, of which the following is a specification.

This invention aims to provide a novel 10 form of spring-actuated curtain roller, adapted to be used, primarily but not exclusively, to operate a curtain on an automobile, for the purpose of shielding the eyes of the driver from the light.

In the drawings:—Figure 1 shows in 15 elevation, a shade roller constructed in accordance with the invention; Figure 2 is a longitudinal section of the roller; Figure 3 is an elevation showing one cap and the head on the end of the shaft; Figure 4 is a cross 20 section on the line 4—4 of Figure 2; Figure 5 is a transverse section showing the casing, the spring anchor and the curtain.

In carrying out the invention, there is provided a tubular casing 1, preferably made of 25 metal, and forming part of the shade roller, the casing having a longitudinal slot 2 and including an end wall 3 carrying a trunnion 4. A cup-shaped cap 5 is mounted on one 30 end of the casing 1, the trunnion 4 extending through the cap, and the cap being held in place by a securing element 6. Circumferentially spaced seats 7 are fashioned in the cap 5. The roller embodies a spring anchor and bearing 8 of U-shape, the member 8 comprising an end plate 9 and arms 10 35 projecting therefrom, the arms having extensions 11 which are trough-shaped in cross section, to fit closely within the casing 1, the longitudinal edges of the extensions 11 being spaced as indicated at 12, securing 40 elements 14 connecting the member 8 to the casing 1 for rotation therewith. A washer 15 abuts against the end of the casing 1 and against the ends of the extensions 11 of the member 8, and has an outwardly extended 45 annular flange 16.

A shaft 17 is located within the member 8 and carries a head 18 disposed within the flange 16 of the washer 15, the head having a hub 19 provided with an opening 20 wherein the shaft 17 is mounted, the hub having openings adapted to receive securing ele-

ments 22, the outer ends of which form fingers 23. A helical spring 24 is disposed within the member 8 and is secured by the 55 elements 22 to the head 18 on the shaft 17, the inner end of the spring 24 being secured at 25 to the member 8, at a point adjacent to the end plate 9, the shaft 17 being extended through the end plate 9 to aid in 60 supporting the roller for rotation. A cap 26 surrounds the casing 1 and aids in holding the securing elements 14 in place. The cap 26 has an inwardly extended flange 27 which overlaps the outer surface of the head 18 on 65 the shaft 17. The numeral 28 marks a flexible curtain having a socket 29 wherein a retaining rod 30 is mounted. The curtain 28 extends through the slot 2 of the roller casing 1, the socket 29 of the curtain being engaged in one of the spaces 12 of the member 8.

Assuming that the trunnion 4 is journaled in one bracket (not shown) and that the fingers 23 are received in another bracket (not shown), it will be obvious that when the curtain 28 is unrolled, the spring 24 will be tensioned, the spring reacting to 70 wind up the curtain.

I claim:—

In a device of the class described, a tubular casing having a longitudinal slot, a combined spring-anchor and bearing, of U-shape, located within the casing and including an end plate and arms projecting 85 from the end plate, the arms having trough-shaped extensions fitting closely in the casing and spaced to register with the slot, for the reception of a curtain, a securing element connecting one extension with the 90 casing, a cap about the casing and retaining the securing element, a cap having an inwardly extended flange, a shaft journaled in the end plate and having an enlarged head journaled between the end of the casing and the flange, and a spring disposed about the shaft and located within the anchor, one end of the spring being connected to the head, and the other end of the spring being connected to one arm of the anchor. 95

In testimony that I claim the foregoing as my own, I have hereto affixed my signature.

ATLEE J. LEWIS.
